Primary Examiner—Terry A. Wallace

(74) Attorney, Agent, or Firm—Jeffrey L. Thompson;
Thompson & Thompson, P.A.(57) **CLAIM**

The ornamental design for a bottle handle, as shown and described.

DESCRIPTION

FIG. 1 is a front perspective view of a bottle handle showing my new design;

FIG. 2 is a rear perspective view of my bottle handle design;

FIG. 3 is a right side elevational view of my bottle handle design;

FIG. 4 is a left side elevational view of my bottle handle design;

FIG. 5 is a front elevational view of my bottle handle design;

FIG. 6 is a rear elevational view of my bottle handle design;

FIG. 7 is a bottom plan view of my bottle handle design;

FIG. 8 is a top plan view of my bottle handle design; and,

FIGS. 9 and 10 are front perspective and front elevational views, respectively, showing my bottle handle attached to a bottle.

The broken lines are for illustrative purposes only and form no part of the claimed design.
